UNITED STATES PATENT OFFICE.

SAMUEL D. STURGIS, OF LOS ANGELES, CALIFORNIA.

METAL-ROLLING MACHINE.

1,062,807.

Specification of Letters Patent. Patented May 27, 1913.

Application filed October 4, 1911. Serial No. 652,805.

To all whom it may concern:

Be it known that I, SAMUEL D. STURGIS, a citizen of the United States, residing at Los Angeles, in the county of Los Angeles 5 and State of California, have invented new and useful Improvements in Metal-Rolling Machines, of which the following is a specification.

This invention relates to improvements in 10 metal rolling machines, and it is an object of the invention to provide a machine for rolling metal pieces to a tapered form without spreading the same to a greater width.

It is also an object of the invention to 15 provide a machine with metal shaping rolls adapted to taper strips of metal without increasing the width thereof, the relative action of the rolls being capable of accomplishing this purpose.

20 In the accompanying drawing forming a part of this specification, Figure 1 is a side elevation of the rolling machine embodying the feature of the present invention. Fig. 2 is a front elevation of the same. Fig. 3 is an enlarged detail sectional view taken transversely through the rolls of the device. Fig. 4 is a detail perspective view of the tapered end of a vehicle spring which has been rolled in the machine.

30 The details of the invention will now be more particularly described, reference being had to the drawing in which—

5 indicates a frame having upright standards 6 and 7 mounted thereon and between 35 which upper and lower metal shaping rolls 8 and 9 are mounted. The rolls are provided with journals engaging any suitable bearings secured in the said frame 6 and 7. The shafts of each roll project beyond the 40 journal portions thereof and are provided with gears 10 and 11 which are arranged to intermesh so that the rolls always turn in a given relation to each other. While intermeshing rolls 10 and 11 upon one side 45 of the machine will be sufficient to accomplish the desired purpose, yet a stronger and more even result is obtained by employing rolls 10 and 11 at both ends of the shafts as shown in Fig. 2. Any desired means for operating the metal shaping rolls through the 50 agencies of said gears may be employed within the spirit of the invention. One practical form has been shown in the drawing which consists of large gears 12 applied to the ends of the lower roll shaft 13. The said gears 12 on each side of the ma-

chine mesh with actuating pinions 14 mounted upon a transverse shaft 15 which is journaled upon a portion of the framing 5. Any suitable mechanism may be employed 60 for rotating the shaft 15 and thus imparting movement to the gearing described and to the shaping rolls 8 and 9.

It is an important feature of the invention that one roll shall have a different action 65 and effect upon the metal to be rolled or shaped from the other roll and the result desired in tapering a metallic spring or other piece of metal without flaring it, is best obtained by making the roll 8 cylindrical, 70 while the roll 9 is of a cam shape, its surface following spiral lines in cross section, whereby an eccentric surface is afforded the roll, preferably like that shown in Fig. 3 of the drawing. 75

To attain the best result the shortest radius of the cam roll should be equal to the radius of the cylindrical roll. As the rolls rotate in unison, the action upon one side of the metal by the roll 8 is different from 80 that of roll 9 upon the lower side of the metal, the said latter roll operating to force or pull the bulk of the metal toward the end of the piece as the spiral increases upon said roll and as its surface draws nearer to the 85 surface of the roll 8.

It is found in practice that an eccentric or cam shaped roll as shown, when operating in conjunction with a cylindrical roll will taper a metallic bar, such for instance 90 as is generally used in making vehicle springs without spreading or giving the said bar a greater width toward its tapered end. Heretofore it has not been possible to roll carriage springs to give them the desired 95 tapered shape without spreading the metal to a considerable degree and rendering it necessary to further operate upon the metal and to trim it or otherwise shape it to the common width of the spring. By means of 100 this construction the above result is possible, since by using a cam roll the shortest radius of which is equal to the radius of an opposing cylindrical roll, the enlarging portion of the cam roll engaging the metal operates to 105 draw the metal lengthwise of a spring instead of spreading it laterally.

It will be observed by reference to Fig. 3 that the metal upon the underside of the spring is forced forward in the form of a 110 thickened or bulged portion which will be carried clear to the end of the spring with-

out the spring broadening. There is usually a slight bulged end left upon the spring which is merely broken off at the end of the tapered part so that the spring appears 5 as shown in Fig. 4 when completed.

In rolling the bars of metal for forming the springs, as soon as the thickest portion of the roll 9 as indicated at 16, passes the point of nearest approach to the roll 8, a 10 bar of metal to be rolled can be thrust between the rolls until it engages a stop 17 secured upon the standards 6 and 7. The continued rotation of the shaping rolls 8 and 9 will then return the bar toward the front 15 of the machine tapering and drawing the metal toward the point or sharpened end thereof.

In order to properly and positively space the shaping rolls 8 and 9 with respect to 20 each other, one roll as 8 is provided with end annular flanges 18 which engage and roll upon cylindrical portions 19 formed at the ends of the eccentric roll 9. The space between the rolls just to one side and off of 25 the thickened portion of the eccentric roll 9 will be the full depth of the annular flanges 18, but the said space will gradually diminish as the rolls turn so as to act upon the metal placed between them and gradually 30 taper it.

It will be understood that metal pieces or strips of different widths may be acted upon in exactly the same manner as described, with respect to the narrow pieces or strips 35 intended for vehicle springs. The action of

the rolls with respect to each other can be somewhat varied by changing their dimensions and also by changing the size of the intermeshing gears 10 and 11 with respect to each other. The best result for rolling 40 springs without flaring them is obtained when the shortest radius of the eccentric roll 9 is equal to the radius of the cylindrical roll 8. By causing the eccentric roll 9 to move somewhat faster than the roll 8, the material of 45 the piece rolled may be drawn outwardly by the eccentric roll so as to even taper the same in width as well as in thickness, or the said roll 9 may be made to go slightly slower than the roll 8 so as to permit a slight flaring 50 of the end of the strip rolled if preferred. Usually when the gears are made of the same size and the shape of the rolls is approximately that shown in the drawing, the strip of metal will be tapered in thickness 55 without changing its width.

What I claim is:—

A mechanism for rolling metal, comprising a cylindrical roll, and a roll having a spiral cross sectional shape the shortest 60 radius of which is equal the radius of the cylindrical roll.

In witness that I claim the foregoing I have hereunto subscribed my name this 26th day of Sept., 1911.

SAMUEL D. STURGIS.
